[57] ABSTRACT

The invention relates to a new series of penicillin esters and salts thereof, to methods of their preparation and to intermediates in the production of the esters of the general formula

in which R₁ and R₂ represent an alkyl radical having from 1 to 6 carbon atoms, a cycloalkyl or cycloalkylalkyl radical the cycloalkyl part having from 3 to 10 carbon atoms, or R₁ and R₂ together with the nitrogen atom represent a heterocyclic ring with from 4 to 8 carbon atoms; R₃ represents radicals known from natural, biosynthetic, and semisynthetic penicillins; and pharmaceutically acceptable salts thereof.

The new compounds are efficiently absorbed from the gastrointestinal tract and after the absorption they are rapidly transformed into the corresponding free penicillins and amidinopenicillanic acids, whereby a broad-spectrum infection can be combated.

**NEW PENICILLIN ESTERS, SALTS THEREOF,
AND METHODS FOR THEIR PREPARATION**

This invention relates to a new series of penicillin esters, to salts thereof and to methods of their preparation.

The new penicillin esters have the general formula I:

in which R₁ and R₂ represent an alkyl radical having from 1 to 6 carbon atoms, a cycloalkyl or cycloalkylalkyl radical the cycloalkyl part having from 3 to 10 carbon atoms, or R₁ and R₂ together with the nitrogen atom represent a heterocyclic ring with from 4 to 8 carbon atoms. In particular, R₁ and R₂, which may be the same or different represent e.g. a methyl, ethyl, propyl, isopropyl, n-butyl, sec.butyl, tert.butyl, one of the isomeric pentyl or hexyl radical, a cyclopentyl, cyclohexyl, 1-adamantyl, 1-bicyclo (2.2.2)-octyl, cyclopentenyl and cyclohexenyl, cyclopentylmethyl, cyclohexylmethyl, cyclopentenylethyl, cyclohexenylmethyl etc., or R₁ and R₂ when taken together with the nitrogen atom represent heterocyclic radicals having from 4 to 8 carbon atoms and optionally containing other hetero atoms in the ring, such as S, O or N, forming more or less hydrogenated ring systems e.g. piperidyl, morpholinyl, hexahydro-1H-azepin-1-yl, or hexahydro-1(2H)-azocinyl. The radicals R₁ and R₂ may be further substituted with halogen atoms, an alkyl, hydroxy, alkoxy, alkylthio group, an acyl group, a carboxy, carbalkoxy, carbamyl, carbamido, cyano or sulfonyl group, or amino- or substituted amino group.

R₃ represents radicals known from natural, biosynthetic and semisynthetic penicillins. Such radicals are e.g. benzyl, phenoxyethyl, 2,6-dimethoxyphenyl, α -azidobenzyl, α -aminobenzyl, α -carboxybenzyl, α -phenoxyethyl, α -phenoxypropyl, 3-phenyl-5-methyl-4-isoxazolyl, 3-(2-chlorophenyl)-5-methyl-4-isoxazolyl, 3-(2,6-dichlorophenyl)-5-methyl-4-isoxazolyl, 3-(2-chloro-6-fluorophenyl)-5-methyl-4-isoxazolyl, 2-ethoxy-1-naphyl, 2-thienylmethyl, 3-thienylmethyl and α -(3-guanyl-1-ureido)-benzyl.

The salts of the new compounds are salts with inorganic or organic pharmaceutically acceptable acids such as hydrochloric acid, hydrobromic acid, sulfuric acid, phosphoric acid, tartaric acid, citric acid, fumaric acid, maleic acid, p-(N,N-dipropylsulfamyl)-benzoic acid and the like acids. When R₁, R₂ and R₃ contain asymmetric carbon atoms the compounds of the invention will exist in different diastereoisomeric forms and the invention comprises all of these forms as well as mixtures thereof. The form in which the compounds

are obtained depends on which enantiomer of the starting materials and which method is used to make the compounds. The mixtures of the diastereoisomers may be separated by fractional crystallization or other known methods.

In contrast to the amidinopenicillanic acids and some of the free penicillins, the compounds of the invention are efficiently absorbed from the gastrointestinal tract and after the absorption they are rapidly transformed into the corresponding free penicillins and amidinopenicillanic acids, either spontaneously or under the influence of enzymes present in the body.

By oral administration the new esters of the invention give rise to high concentrations of the corresponding free penicillins and amidinopenicillanic acids in the blood and tissues due to efficient absorption combined with rapid hydrolysis in the organism, whereby a broad-spectrum infection can be combated, due to the fact that the amidinopenicillins possess strong antibacterial effect especially on gramnegative bacteria.

It has also been found that by the simultaneous high concentrations of these two types of antibiotics a synergistic effect is obtained (for instance by administration of the compound of formula I in which R₁R₂N- stands for a hexamethyleneimine radical and R₃ is benzyl).

The compounds of formula (I) are well tolerated compounds which are administered in clinical practice either as such or, preferably, in the form of one of their salts mixed with carriers and/or auxiliary agents and in any suitable form of pharmaceutical presentation for oral use, such as tablets, pills or dragees, or can be filled in medical containers such as capsules, or as far as suspensions are concerned, filled into bottles. Pharmaceutical organic or inorganic, solid or liquid carriers suitable for oral administration can be used to make up the composition. Gelatine, lactose, starch, magnesium stearate, talc, vegetable and animal fats and oils, gum, polyalkylene glycol, or other known carriers for medicaments are all suitable as carriers. The preferred salt of the esters is the hydrochloride, but salts with other inorganic or organic acids may be used as mentioned above. Furthermore, the compositions may contain other pharmaceutically active components which can appropriately be administered together with the ester in the treatment of the infectious diseases.

The compounds of the invention can be prepared by several methods. In the first method, a salt of a penicillin of the general formula II is reacted with a compound of the general formula III

in which formulae R₃ is as defined above, X is a cation such as potassium, sodium, ammonium or trialkylammonium ion and Y represents a bromine atom, or iodine atom, an alkylsulphonyloxy group or an arylsulphonyloxy group, preferably in an inert organic solvent, e.g. dimethylformamide or acetone, and at room temperature or at slightly elevated temperatures,

whereby a compound of the general formula IV, in which R_3 is as defined above, is obtained:

IV

The compounds of formula IV are then reacted with a salt of a compound of the general formula V:

V

in which R_1 , R_2 and X are as defined above, at room temperature or at slightly elevated temperatures, whereby a compound of formula I is obtained.

The compounds of formula V are disclosed in the following section, or perhaps better, subsection. It will be noted that the section refers to the subject matter with which it deals, including the compounds of the above formula V and related compounds and their method of making, as "the invention" and "this invention," which in this case is a convenient term of reference, not intended to indicate that the subject matter of this section A is an invention that anyone is seeking to patent in this present application. To distinguish the various formulae, examples and R numbers, etc. in this section A from those in the rest of the specification; the ones in the section are being given the suffix a. It will be noted that formula Ia, when R_{4a} makes a salt of the hydroxide and R_{3a} is hydrogen, corresponds to formula V except for the greater breadth of R_{1a} and R_{2a} as compared to R_1 and R_2 . The particular interrelation between formula IIa and formula IX will also be noted.

Section A Devoted to the Intermediates of Formula V and their Method of Making

This invention relates to once unknown derivatives of 6-aminopenicillanic acid, to pharmaceutically acceptable salts thereof, and to methods for the production of these same compounds.

The compounds of the invention have the general formula:

(Ia)

in which R_{1a} and R_{2a} represents the same or different substituents and each represents an aliphatic hydrocarbon radical, an aralkyl radical, a cycloalkyl radical, a heterocyclically substituted alkyl radical; R_{1a} and R_{2a} together with the nitrogen atom represent a ring system; R_{1a} and R_{3a} together with the N-C atoms represent a ring system; R_{3a} can furthermore be hydrogen or have the same meaning as R_{1a} ; R_{4a} represents a hydroxyl group, an esterified hydroxyl group, or a substituted or unsubstituted amino group radical.

More particularly, R_{1a} , R_{2a} and R_{3a} represent an aliphatic hydrocarbon radical in which the carbon chain can be straight or branched, saturated or unsaturated, and may be interrupted by an oxygen or sulphur atom, such as methyl, ethyl, propyl, isopropyl, butyl, sec. butyl, tert. butyl, pentyl, hexyl, dodecyl, allyl, butenyl, pentenyl, propargyl, methoxyethyl, ethoxyethyl, methylthioethyl and the like; an aralkyl radical, such as mono or bicyclic aralkyl radical, e.g. benzyl, phenyl-ethyl, 1- or 2-naphthylmethyl; a cycloalkyl or cycloalkyl-alkyl radical, having from 3 to 10 ring members and being saturated or having one or two double bonds, such as cyclopentyl, cyclohexyl, 1-adamantyl, 1-bicyclo(2.2.2)octyl, cyclopentenyl and cyclohexenyl; a heterocyclically substituted alkyl radical in which the heterocyclic part can have from 5 to 10 atoms in the ring and can contain further hetero atoms, for example, oxygen, sulphur, or nitrogen, such as pyridyl, pyrazinyl, pyrimidyl, pyrrolidyl, piperidyl, hexamethylenimine, heptamethyleneimine, morpholinyl, thiazinyl, furyl, thienylquinolyl, in all of which the hetero atoms may be placed in any of the available positions; R_{1a} and R_{2a} together with the nitrogen atom, or R_{1a} and R_{3a} together with the N-C atoms represent heterocyclic ring systems having from 5 to 10 atoms and optionally containing other hetero atoms in the ring, such as S, O, or N, forming more or less hydrogenated ring systems e.g. piperidyl, morpholinyl, hexa- or heptamethyleneimine. All the radicals R_{1a} , R_{2a} and R_{3a} may be further substituted with halogen atoms, alkyl groups or alkoxy groups.

More particularly, R_{4a} represents a hydroxyl group, a substituted hydroxyl group OR_{5a} in which R_{5a} stands for an alkyl radical, aryl radical, aralkyl radical, an alkyl radical substituted with alkoxy, alkanoyl, aroyl, cyano, or a carbalkoxy group, e.g. methyl, ethyl, phenyl, benzyl, methoxymethyl, acetonyl, phenacyl, cyanomethyl, carbethoxymethyl, or dicarbethoxymethyl and the like; R_{5a} further represents an acyloxymethyl radical the acyl part of which being an aliphatic, alicyclic, aromatic, ar-aliphatic or heterocyclic radical, such as acetyl, propionyl, butyryl, pivaloyl, cyclohexylacetyl, benzoyl, phenylacetyl, picolinyl, nicotinyl, furylacetyl, thienylacetyl etc., or R_{4a} can represent an $NR_{6a}R_{7a}$ radical, in which R_{6a} and R_{7a} are hydrogen, or have the same meanings as defined for R_{1a} or together with the nitrogen atom form a ring in the same manner as defined for $R_{1a}R_{2a}N$.

The compounds of formula Ia may be isolated as such or in the form of a salt with a pharmaceutically acceptable acid, such as hydrochloric acid, phosphoric acid, nitric acid, acetic acid, propionic acid, citric acid, tartaric acid, maleic acid, etc. When R_{4a} stands for a hydroxyl group the compounds of formula Ia may be isolated as the acid and as a salt thereof, preferably the alkali metal salts and the ammonium salts.

The invention comprises all possible isomeric forms of the compound of formula Ia.

The invention also comprises methods for the preparation of the above described compounds. In a preferred method the compounds of formula Ia are prepared in two steps from amides of the general formula II:

65

(IIa)

in which R_{1a} , R_{2a} and R_{3a} have the meanings defined above. These starting materials are known or may be prepared by methods known from generally used textbooks. By a generally known reaction these amides can be transferred into the corresponding amide halides, some of which are also known compounds, having the formula IIIa:

in which R_{1a} , R_{2a} and R_{3a} have the above given meaning and Hal stands for halogen, preferably chlorine or bromine. All well-known halogenating agents can be used, but it is preferable to use halogenating agents, which throughout the course of the reaction form gaseous by-products, such as phosgene or oxalyl chloride or bromide but also others, e.g. thionyl halides, may be used. The reaction can be performed in inert, dry, organic solvents, e.g. ether or toluene, in which the amide halide in most cases will be insoluble and from which it can be isolated by filtration after the reaction is completed. The compounds of formula III are hygroscopic and rather unstable and are therefore preferably used in the next step without purification.

In the next step the amide halide is reacted with a compound of the general formula IVa, yielding the compounds of the invention:

in which R_{4a} has the meaning defined above. The reaction is performed at low temperature and in inert organic solvents, which are dry and free from traces of alcohols, preferably chloroform, in which the reaction components are soluble, but solvents in which the amide halide is insoluble, e.g. ether, may be used as well. The reaction is performed under cooling and in the presence of at least one equivalent of a tertiary amine. In the case where one equivalent of the tertiary amine is used, the reaction product will be isolated as the hydro halide, whereas the free amidines will be obtained when two or more equivalents of the tertiary amine are used.

The reaction time depends on the reactants, the temperature and the solvents used in the process. In the case where R_{4a} stands for a hydroxyl group, it is preferred to protect the carboxyl group with a trimethylsilyl radical which, after the reaction easily can be split off again. The preparation of the trimethylsilyl ester of 6-aminopenicillanic acid is known from the literature. The trimethylsilylester of the amidine is preferably cleaved by a hydrolysis or an alcoholysis under mild conditions.

The reaction products of formula Ia can be purified and isolated in usual manner and may be obtained either in free state or in the form of a salt. The free acid can also be obtained from some of the esters by an enzymatic hydrolysis or a mild hydrogenolysis, and if the

free acid is the reaction product the esters and the amides can be prepared therefrom by methods known from the literature.

- The compounds of formula IVa are partly known compounds and may be prepared by esterification or amidation of 6-aminopenicillanic acid or a protected 6-aminopenicillanic acid, such as the 6-trityl derivative thereof. The trityl group may be split off after the reaction under conditions not affecting the lactam ring.
- 5 They can also be prepared by esterification or amidation of the generally industrially used penicillins, whereafter the acyl side chain can be split off chemically or enzymatically under such conditions that the ester group or the amide group is not affected.
- 10 15 The invention will be further described in the following Examples:

EXAMPLE Ia

Pivaloyloxymethyl 6-[(hexahydro-1H-azepin-1-yl)-20 methyleneamino]-penicillanate

12.7 g. of N-formylhexamethyleneimine was dissolved in 250 ml. of dry ether. While stirring and cooling, 8.5 ml. of oxalyl chloride in 50 ml. of dry ether was added dropwise. The mixture was stirred overnight at room temperature. The precipitated amide chloride was filtered off and washed with dry ether, and was placed in an exsiccator.

25 27.5 g. of pivaloyloxymethyl 6-aminopenicillanate tosylate was suspended in 1,500 ml. of ethyl acetate under continuous stirring and cooling in an ice bath. 950 ml. of ice-cold aqueous sodium bicarbonate (2 per cent) was added. The ethyl acetate layer was separated and was shaken with 750 ml. of ice-water containing 25 ml. of aqueous sodium bicarbonate (2 per cent), whereafter it was dried over magnesium sulfate at 0°C. After filtration the solution was evaporated to dryness in *vacuo*. The residue was dissolved in a solution of 15.5 ml. of dry triethylamine in 75 ml. of dry alcohol-free chloroform. To this solution 10 g. of the above prepared amide chloride dissolved in 75 ml. of dry alcohol-free chloroform was added dropwise at a temperature of about -20°C. After standing for half an hour at -20°C., the temperature was raised to 0°C. within 15 minutes. The solution was evaporated to dryness in *vacuo*. The residue was stirred with 750 ml. of ether. Undissolved triethylamine hydrochloride was filtered off, and the filtrate was again evaporated to dryness in *vacuo*. The residue was reprecipitated from acetone (200 ml.) — water (150 ml.). After recrystallization from cyclohexane an analytically pure product was obtained with a melting point of 118.5°-119.5°C. and $[\alpha]_D^{20} : +231^\circ (c=1, 96\% \text{ ethanol})$.

30 35 40 45 50 The starting material N-formylhexamethyleneimine was prepared from hexamethyleneimine and chloral and had a boiling point of 111°-112°/10 mm Hg.

EXAMPLE 2a

Pivaloyloxymethyl 6-(N,N-dimethylformamidino-N')-penicillanate hydrochloride.

55 60 65 6.8 g. of chlorodimethylformiminium chloride was dissolved in 40 ml. of dry alcohol-free chloroform. At a temperature of -30° to -40°C. this solution was added dropwise to a solution of 13.3 g. of pivaloyloxymethyl 6-aminopenicillanate and 12.4 ml. of triethylamine in 75 ml. of dry, alcohol-free chloroform while stirring. The temperature was raised to 0°C. within 1 hour. The solution was evaporated in *vacuo* and the

residue was treated with 200 ml. of dry ether. After filtration from triethylamine hydrochloride, the filtrate was evaporated in vacuo. The oily residue was dissolved in 40 ml. of isopropanol. At 0°C. and while stirring, 4 ml. of a solution of dry hydrogen chloride in isopropanol (9N) was added dropwise. Thereafter 150 ml. of ether was added. After filtration, washing with ether and recrystallization from acetone-ether, the compound was obtained in analytically pure form having a melting point of 146°C.. $[\alpha]_D^{20} : + 209^\circ$ (c=1, 96% C_2H_5OH).

EXAMPLE 3a

Pivaloyloxymethyl 6-(N,N-dimethyl-phenylacetamidino-N')-penicillanate nitrate.

14 ml. of a solution of phosgene in dry toluene, containing 2.2 g. of phosgene, was slowly added to a solution of 3.3 g. of N,N-dimethyl-phenylacetamide in 10 ml. of dry toluene with stirring and ice-cooling. Stirring was continued for 2 hours at room temperature, whereupon the amide chloride formed was quickly isolated by filtration with suction, washed with dry ether and kept in an exsiccator.

2.2 g. of the crude amide chloride was dissolved in 35 ml. of dry, alcohol-free chloroform. While stirring and maintaining the temperature at -30°C., this solution was slowly added to a solution of triethylamine (3.1 ml.) and pivaloyloxymethyl 6-aminopenicillanate in 15 ml. of dry, alcohol-free chloroform, prepared from 5.5 g. of the p-toluenesulfonate of the amine as described in Example 1a. The temperature was raised to 0°C. during three-fourth hour. After evaporating in vacuo, the residue was triturated with 200 ml. of ether. The precipitate was removed by filtration and the filtrate evaporated in vacuo. The residue was dissolved in 250 ml. of ether and filtered with "Dicalite" filter aid (diatomaceous earth).

0.35 ml. of concentrated nitric acid was dissolved in 10 ml. of dry ethanol and slowly added to the filtrate with stirring and ice-cooling. The precipitate formed was isolated and treated with 30 ml. of methylene chloride which leaves most of the nitrate of the unreacted pivaloyloxymethyl 6-aminopenicillanate undissolved. After filtration and evaporation in vacuo of the filtrate, the residue was twice recrystallized from acetone-ether yielding an analytically pure product with a melting point of 146.5°-147° C.. $[\alpha]_D^{20} : 187^\circ$ (c=1, 96% C_2H_5OH).

EXAMPLE 4a

Cyanomethyl 6-(N,N-diethylformamidino-N')-penicillanate oxalate.

A. Cyanomethyl 6-aminopenicillanate p-toluenesulfonate.

To a stirred suspension of 6-aminopenicillanic acid (43.3 g) in dimethylformamide (400 ml.) at room temperature was added triethylamine (35 ml.) and chloroacetonitrile (25.5 ml.). Stirring was continued at room temperature for 24 hours. The mixture was diluted with 400 ml. of ethyl acetate, and filtered. The solid was washed with ethyl acetate. The filtrate was diluted with 800 ml. of ethyl acetate, extracted 4 times with 200 ml. of water and dried over magnesium sulfate. After filtration an 0.5 M solution of p-toluenesulfonic acid in ethyl acetate (320 ml.) was added with stirring. The precipitate was filtered off and washed with ethyl acetate and ether. Recrystallization from

methanol-ethyl acetate afforded a colourless analytically pure product, melting at 154.5°-156° C (dec.) $[\alpha]_D^{20} : + 146^\circ$ (c=1, 96% C_2H_5OH).

B. Chlorodiethylformiminium chloride.

- 5 1.7 ml. of oxalyl chloride dissolved in 10 ml. of dry ether was slowly added to a solution of 2.2 ml. of diethylformamide in 50 ml. of dry ether at 0°C. with stirring. After stirring at room temperature for three-fourths hour, the precipitate was quickly filtered with 10 suction, washed with dry ether and stored in an exsiccator.
- C. Cyanomethyl 6-(N,N-diethylformamidino-N')-penicillanate oxalate.

Cyanomethyl 6-aminopenicillanate was liberated 15 from 4.7 g. of the p-toluenesulfonate according to the procedure of Example 1 and dissolved in 15 ml. of dry, alcohol-free chloroform. Dry triethylamine (3.1 ml.) was added and the solution was cooled to -30°C.. A solution of 1.7 g. crude amide chloride in 15 ml. of dry, 20 alcohol-free chloroform was slowly added at -20°C. to -30°C., with stirring. In the course of three-fourths hour the temperature was allowed to raise to 0°C. The solution was evaporated in vacuo and the residue triturated with 200 ml. of ether. After filtration and evaporation in vacuo of the filtrate, the residue was dissolved 25 in 200 ml. of ether and treated with "Dicalite" filter aid (diatomaceous earth). A solution of 0.85 g. of anhydrous oxalic acid in 50 ml. of ether was slowly added to the filtrate with stirring. When the precipitate had 30 settled, the supernatant liquor was decanted and the precipitate stirred with fresh ether. After filtration, the product was recrystallized twice from acetone-ether to yield the analytically pure material melting at 121°-122.5° C.. $[\alpha]_D^{20} : + 214^\circ$ (c=1, 96% C_2H_5OH).

EXAMPLE 5a

γ -Phenylpropyl 6-[(hexahydro-1H-azepin-1-yl)-methylene-amine]-penicillanate hydrochloride

A. γ -Phenylpropyl 6-aminopenicillanate.

- 40 To a stirred suspension of 6-aminopenicillanic acid (21.6 g.) in dimethylformamide (200 ml.) triethylamine (11.4 ml.) and γ -bromophenylpropane (22.0 g.) was added at room temperature. Stirring was continued at room temperature for 18 hours. 200 ml. of ethyl acetate was added and the mixture filtered. The filtrate was diluted with 400 ml. of ethyl acetate, extracted four times with 100 ml. of water and dried over magnesium sulfate. After evaporation in vacuo, the oily residue was dissolved in a mixture of water and ether (200 ml. of each) with stirring and ice-cooling. By slow addition of diluted hydrochloric acid the pH was adjusted to 3 to 4. The aqueous phase was separated, made alkaline to a pH of about 7.5 by addition of sodium bicarbonate and extracted with ether. After drying, the ether was evaporated in vacuo to leave the crude ester as an oil.

B. γ -Phenylpropyl 6-[(hexahydro-1H-azepin-1-yl)-methyleneamino]-penicillanate hydrochloride.

- 55 2.2 g. of the crude ester and 2.0 ml. of dry triethylamine were dissolved in 15 ml. of dry, alcohol-free chloroform and cooled to -60°C. with stirring. A solution of 1.2 g. of the amide chloride described in Example 1a in 10 ml. of dry, alcohol-free chloroform was slowly added. The temperature was raised to 0°C. during 1 hour, whereupon the solution was evaporated in vacuo. After trituration with 80 ml. of ether, the solid formed was filtered off. The filtrate was extracted with 80 ml.

of water with stirring and ice-cooling, while the pH of the aqueous phase was lowered to about 3. The aqueous phase was separated, made alkaline with sodium bicarbonate and extracted with ether. After drying, the ether was evaporated in vacuo. The oily residue was dissolved in 10 ml. of isopropanol and treated with 0.35 ml. of a solution of dry hydrogen chloride in isopropanol (9N), with stirring and ice-cooling. The precipitate was filtered off and washed with a little isopropanol. Two recrystallizations from methanol-ether yielded an analytically pure product melting at 163.5°C.. $[\alpha]_D^{20}$: + 201 (c=1, 96% C_6H_5OH).

EXAMPLE 6a

6-[(Hexahydro-1H-azepin-1-yl)-methyleneamino]-penicillanic acid

A solution of the amide chloride described in δ 1a (4.6 g) in dry, alcohol-free chloroform (20 ml.) was added slowly 5.18 a solution of trimethylsilyl 6-aminopenicillanate (7.2 g.) and triethylamine (3.5 ml.) in dry, alcohol-free chloroform (50 ml.) with stirring and cooling to $-70^{\circ}\text{C}.$ The temperature was raised to $0^{\circ}\text{C}.$ during $1\frac{1}{2}$ hours. The solution was evaporated to dryness in *vacuo* and the residue was triturated with dry ether (200 ml.). The precipitate was filtered off and washed with dry ether. The filtrate was diluted with ether (200 ml.). 2-Butanol (2.8 ml.) was added drop-wise with stirring and cooling to $0^{\circ}\text{C}.$ The stirring was continued for one-fourth hour at $0^{\circ}\text{C}.$, whereupon the precipitate was filtered off, washed with ether and dried. It was a white, amorphous powder, soluble in water. Paper chromatography was performed using the descending technique on Whatman No. 1 paper with the solvent system n-butanol-ethanol-water (4:1:5). The R_f value was 0.5.

In a second method a compound of formula V is reacted with a compound of formula III - under conditions like those described for the reaction between II and III - to yield a new compound of the general formula VI:

in which R_1 and R_2 are as defined above. These compounds are new and being interesting intermediates in the preparation of the compounds of this invention, they also constitute part of the invention. 45

Reaction between a compound of formula II and a compound of formula VI — under conditions like those described above for the reaction between IV and V — yields a compound of formula I.

In a third method a compound of formula VII:

in which X is as defined above and R₄ represents a hydrogen atom or a protecting group such as trityl, carbobenzoxy or the like, is reacted with a compound of the above formula IV to yield a compound of the general formula VIII:

in which R_3 and R_4 are as defined above.

The compounds of formula VIII are described in the following Section B, or perhaps rather subsection. The compounds which it describes are in places described as "the compounds of the invention" or the like, but this is merely for convenience in designation and does not mean that they are among those compounds on which a patent is being sought in this application. To distinguish the formula numbers, the Example numbers and the R numbers and the like from those elsewhere in this application, the suffix b has been appended to them. As will be noted, the compounds of formula VIIb are those of formula VIII when R_{3b} is hydrogen and R_4 is hydrogen.

Section B as to the Compounds of Formula VIII

This invention relates to a series of penicillin esters, to salts thereof and to methods of their preparation.

The said penicillin esters have the general formula:

in which R_{1b} and R_{2b} are radicals known from bisynthetic, semi-synthetic and naturally occurring penicillins, such as alkyl, aryl or aralkyl radicals optionally substituted with hydroxy and etherified hydroxy, halogen, amino, azido, heterocyclic or spirocyclic radicals, for instance a benzyl radical, a phenoxyethyl radical, a dimethoxyphenyl radical, an alphaazidobenzyl radical, an alpha-aminobenzyl radical, a betaamino-alpha-phenylethyl radical, an alpha-amino-spirocyclopentyl radical, and other radicals containing one or two amino groups. R_{1b} and R_{2b} may represent the same or different radicals but at least one of them shall contain an amino group; R_{3b} is hydrogen or a lower alkyl radical, a halolower alkyl radical, an aryl radical or an aralkyl radical, such as methyl, ethyl, propyl, isopropyl, trichloro-

15 in which formula R_b represents either R_{1b} or R_{2b} which are as defined above, or a radical which can be converted into R_{1b} or R_{2b} such as radicals containing a protected amino group or a group which can be converted into an amino group e.g. azido, nitro or halogen; X_b is a cation such as a potassium, sodium, ammonium or trialkylammonium ion, and Y_{1b} and Y_{2b} individually represent chlorine, bromine, iodine, alkylsulfonyloxy or arylsulfonyloxy groups. The compounds of formula IIIb are, for instance, methylene iodide, methylene bromide, chloriodomethane, bis-methanesulfonyloxy methane or bis-toluenesulfonyloxy methane. In the case where the Y_{1b} and Y_{2b} are the same, the reaction with a compound of formula IIb gives compounds of formula IVb

20

25

methyl, trifluoromethyl, phenyl and benzyl radicals.

The salts of the said compounds are salts with inorganic or organic pharmaceutically acceptable acids such as hydrochloric acid, hydrobromic acid, sulfuric acid, phosphoric acid, tartaric acid, citric acid, fumaric acid, maleic acid and the like acids.

When R_{1b} and/or R_{2b} contain asymmetric carbon atoms or when R_{3b} is different from hydrogen and R_{1b} different from R_{2b} the compounds of the invention will exist in different epimeric forms and the invention comprises these epimers as well as mixtures thereof. The form in which the compounds are obtained depends on which enantiomer of the starting materials and which method is used to make the compounds. The mixtures of the epimeric forms may be separated by fractional crystallization or other known methods.

The compounds of the invention can be prepared by reacting a salt of a penicillin of the general formula IIb with a compound of the general formula IIIb

45 in which R_b contains one or more protected amino groups or groups which can be converted into an amino group. From these intermediates the compounds of the invention in which R_{1b} and R_{2b} are the same are obtained after cleavage of the protecting group or by conversion of one of the groups mentioned above into an amino group. Compounds of the invention in which R_{1b} and R_{2b} are different may also be produced by resulting the corresponding penicillin salts, if necessary in a protected form, in two steps with a compound of formula IIIb ($Y_{1b}=Y_{2b}$) when an excess of that compound is used and the reaction is performed under sufficiently careful and mild conditions. It is, however, more advantageous in these cases to use compounds of formula IIIb in which Y_{1b} and Y_{2b} are different, for example chloriodomethane because the reactivity of the chlorine atom is less than that of the iodine atom, and the first reaction step therefore, yields an ester of the penicillin used in the reaction having the formula Vb:

50

55

60

Compounds of formula Vb react easily with a penicillin salt of formula IIb in which R_b may be the same as, or different from, the first R_b , thereby intermediate of formula IVb are obtained. These can be converted into the compounds of the invention as described above. The reactions are performed in inert organic solvents such as dimethylformamide or acetone and at room temperature or at slightly elevated temperatures. In some cases the intermediates of formula IVb are not isolated but directly converted into the compounds of the invention. The isolation of the reaction products is done in usual manner and if the epimers are to be separated this can be done, for instance, by means of fractional crystallization in suitable solvents.

It will appear from the description above that in the case where amino groups are present in the R_{1b} and R_{2b} radicals, these amino groups are preferably protected during the reactions or are replaced by groups which can be converted to amino groups as a last step of the synthesis.

As a common characteristic of such groups, which in the following are called Z_b it can be said that Z_b is selected from groups which are capable of being converted to an amino group by means of methods mild enough to avoid destruction of the molecule at the ester group or at the lactam ring. In particular, Z_b is a benzyloxycarbonyl-amino radical, a p-halo-, p-nitro-, or p-methoxy-benzyloxy-carbonylamino radical, a β,β,β -trichloro-ethoxycarbonyl-amino or an allyloxycarbonyl-amino radical; or Z_b is a sulphur containing radical, such as a tritylsulphenyl-amino or arylsulphenylamino radical, i.e. an o-nitrophenylsulphenylamino radical; Z_b may also be a tritylamin radical, a tertiary butoxycarbonyl-amino radical, or a radical obtained by reacting the free amino group with a β -dicarbonyl compound such as acetylacetone, an acetoacetic

or Raney Nickel, but other catalysts can also be used. Electrolytic reduction can also be used in these cases. When Z_b stands for a β,β,β -trichloroethoxycarbonyl-amino radical, reduction with zinc in acetic acid is preferred. A mild acid hydrolysis is preferred in the case where Z_b stands for a sulphur-containing radical, an enamine or a Schiff base, for instance at a pH of about 2 in a diluted solution of hydrogen chloride preferably in aqueous tetrahydrofuran. An acid hydrolysis, for instance with hydrochloric acid, acetic acid, p-toluenesulfonic acid or trifluoroacetic acid can also be used for elimination of the trityl and tert.butoxycarbonyl radical. Also known from the literature is the removal of the o-nitrophenylsulphenyl radical involving a nucleophilic attack on the sulphur atom of the sulphenamide group, the best yield in the present case being obtained with sodium or potassium iodide, sodium thiosulphate, sodium hydrogen sulphite, sodium dithionite or potassium thiocyanate. Other sulphenamide radicals can be split in the same way. If Z_b is an azido or a nitro group or a hydrogen atom, especially a bromine atom, these groups may be transformed into the free amino group in a known manner, the azido and the nitro group by a catalytic hydrogenation with a noble metal catalyst or with Raney-Nickel or by an electrolytic reduction, and the halogen atom by an amination, for instance with hexamethylenetetramine.

In the case where one or both of the radicals R_{1b} and R_{2b} contain a free hydroxy group it can be protected during the reaction by generally known methods, e.g. by etherification or acylation.

The compounds of the invention can also be prepared from 6-aminopenicillanic acid which, in the form of a salt, reacts with the compounds of formula IIIb to form an ester of the following formula VIb:

ester or benzoylacetone to form enamines or Schiff bases. In general, any group represented by Z_b which can be converted by reduction, by mild acid hydrolysis or by other mild reactions known per se, into an amino group will be suitable, since experiments have shown that the esters of formula Ib formed by the reaction in question are stable under such conditions.

The conversion of Z_b into an amino group can be effected by different procedures depending on what Z_b stands for. Catalytic hydrogenation will be preferred when Z_b stands for benzyl-oxycarbonyl-amino and related derivatives thereof, and for trityl-amino. This hydrogenation is preferably performed at room temperature and at atmospheric or slightly elevated pressure in a solvent which may be a non-reducible organic solvent or a mixture thereof with water. The preferred catalysts are noble metal catalysts such as palladium or platinum

55 in which R_{3b} is as defined above. The amino groups are preferably, but not necessarily, protected for instance with a triphenylmethyl radical and the process can be performed under reaction conditions similar to those described above for the reaction between compounds of formulae IIb and IIb.

The above compounds of formula VIb can also be produced by reacting salts of industrially available penicillins, for example benzylpenicillin, with a compound of formula IIIb under the reaction conditions already described to yield a compound of formula IVb in which R_b is e.g. benzyl. The side chains of these compounds are subsequently split off enzymatically or chemically. 60 The preferred method consists of reacting the 6-acylamino-penicillanic acid ester with an acid halide in the presence of an acid-binding agent, such as quinoline or pyridine, and the like. The preferred acid halide

is, however, phosphorus pentachloride, because the reaction in this case can be performed at low temperature increasing the stability of the intermediate formed, which presumably is an imino halide. The reaction can be performed in different solvents, but the preferred are chloroform and methylene chloride.

The intermediate is not isolated but is treated with an excess of a primary alcohol to form an imino ether. The reaction temperature and the reaction time depend on the alcohol used; in most cases temperatures from -20°C to $+20^{\circ}\text{C}$ will be convenient.

The imino ether is not isolated, but subjected to an acid alcoholysis or hydrolysis, whereby the $\text{C}=\text{N}$ bond is cleaved to yield the corresponding 6-amino-penicillanic ester of formula VIb. It is surprising that the lactam ring and the acyloxymethyl ester grouping are sufficiently stable under these conditions. By the generally used methods the esters of 6-amino-penicillanic acid can be isolated from the reaction mixture as such or in the form of a salt with an inorganic or organic acid such as the hydrochloride or the tosylate.

The compounds of formula VIb are such and being important intermediate in the preparation of the compounds of the invention they also constitute a part of this invention.

In the method of preparing the intermediates of formula VIb, Y_{1b} and Y_{2b} in the compounds of formula IIIb can be the same or different. If Y_{1b} is substantially more reactive than Y_{2b} the reaction will be a two-step process and the first reaction product will be an α -Y_{2b} ester of 6-amino-penicillanic acid or a protected 6-amino-penicillanic acid. Both these esters and the above described corresponding esters of formula Vb are such compounds which also constitute a part of this invention. It is evident that they are especially valuable intermediates for the preparation of compounds of the invention in which R_{1b} and R_{2b} are different. The esters of 6-aminopenicillanic acid in free or protected form can be reacted with a salt of a penicillin of formula IIb whereby, if necessary after elimination of a protecting group on the amino group, a compound of the following formula VIIb is obtained:

in which R_b and R_{3b} are as defined above. Compounds of formula VIIb can also be obtained from compounds of formula IVb in which R_b e.g. is benzyl by a modification of the method used for removal of the side chain described above.

These intermediates can thereafter be reacted with reactive derivatives of acids of the formula R_b-COOH such as acid halides, acid anhydrides or mixed anhydrides in which R_b is as defined above, whereby the compounds obtained are either the compounds of the invention or the corresponding compounds having pro-

5 tected groups which, in the manner already described, can be converted to the compounds of the invention.

The invention will now be illustrated by the following non-limiting Examples:

EXAMPLE 1b

A. Bis-[6 β -(D- α -azidophenylacetamido)-penicillanoyloxy]-methane

10 A mixture of potassium D- α -azidobenzylpenicillinate (10.0 g.) and chloroiodomethane (1.0 ml.) in dimethylformamide (DMF) (50 ml.) is stirred for 3 days at room temperature.

15 Thereafter, the mixture is diluted with ethyl acetate, filtered, and the filtrate washed with water, aqueous sodium bicarbonate and water. The organic phase is dried and evaporated in vacuo to yield the desired product as a brownish amorphous product, which could be used for the next step without further purification.

20 The IR-spectrum (CHCl₃) shows strong bands at: 2110, 1780, 1690 and 1510 cm⁻¹.

25 The NMR-spectrum (CDCl₃) shows signals at δ = 1.53 and 1.65 (2s), 4.50 (s), 5.13 (s), 5.50-5.90 (m), 5.90 (s), 7.15 (d), J = 10, 7.42 (s) (TMS as internal standard).

B. Bis-[6 β -(D- α -aminophenylacetamido)-penicillanoyloxy]-methane, dihydrochloride

30 A solution of bis-[6 β -(D- α -azidophenylacetamido)-penicillanoyloxy]-methane (5.1 g.) in ethyl acetate (100 ml.) is placed in a three-necked 500 ml. flask equipped with a gas inlet - outlet tube, a glass-calomel combination electrode, a burette and a magnetic stirrer. Water (100 ml.) and 10% palladium on carbon catalyst (3 g.) are added. The system is flushed with nitrogen, whereafter a stream of hydrogen is bubbled through the suspension while stirring, a pH-value of 2.5 being maintained in the suspension by the addition of 0.5 N hydrochloric acid (40 ml.). When the consumption of acid has ceased, the catalyst is filtered off. The aqueous phase is separated and freeze-dried to afford the desired compound as a colourless amorphous product.

35 The IR-spectrum (KBr) shows strong bands at: 1770-1790 (broad) and 1690 cm⁻¹.

40 The NMR-spectrum (CD₃OD) shows signals at δ = 1.42 and 1.47 (2s), 4.43 (s), 5.18 (s), 5.55 (dd, J = 4.5), 5.90 (s), 7.53 (s). (TMS as internal standard).

EXAMPLE 2b

A. 6 β -(D- α -azido- α -phenylacetamido)-penicillanoyloxymethyl phenoxyethylpenicillinate

45 To a solution of chloromethyl phenoxyethylpenicillinate (0.4 g.) - prepared as described below - in di-

methylformamide (6 ml.) is added potassium D- α -azidobenzylpenicillinate (0.42 g.). After stirring overnight at room temperature, the mixture is diluted with ethyl acetate (20 ml.) and extracted with water (2 $\times$ 5 ml.), 2% aqueous sodium bicarbonate (5 ml.) and water (2 $\times$ 5 ml.). The organic phase is dried and evaporated to dryness in vacuo to yield the desired compound as an amorphous powder.

The IR-spectrum (CHCl₃) shows strong bands at 2130, 1785, 1693, 1515, 1498 and 980 cm⁻¹.

The NMR-spectrum (CDCl₃) shows peaks at δ = 1.53 (s), 1.60 (s), 1.66 (s), 4.50 (s), 4.55 (s), 5.13 (s), 5.40–5.90 (m), 5.90 (s), 6.80–7.50 (m) and 7.43 (s), TMS being used as internal reference.

Preparation of the starting material:

Chloromethyl phenoxyethylpenicillinate

To a solution of phenoxyethylpenicillin (70 g.) and triethylamine (29.4 ml.) in dimethylformamide (250 ml.) is added chloroiodomethane (80 ml.) and the mixture is stirred for 3.5 hours at room temperature. Thereafter, the mixture is diluted with ethyl acetate (500 ml.) and ether (500 ml.), filtered, and the filtrate washed with water (3 $\times$ 250 ml.), 0.5 M aqueous sodium bicarbonate (100 ml.), and water (2 $\times$ 100 ml.). The organic phase is dried and evaporated in vacuo to yield the crude ester as a brownish gum, which can be used for the next step without further purification.

B. 6 β -(D- α -amino- α -phenylacetamido)-penicillanoyloxymethyl phenoxyethylpenicillinate, hydrochloride

This compound is obtained from 6 β -(D- α -azido- α -phenylacetamido)-penicillanoyloxymethyl phenoxyethylpenicillinate by catalytic reduction, performed as described in Example 1b B. The aqueous phase is separated and freeze-dried to afford the desired compound as a colourless amorphous powder.

The IR-spectrum (KBr) shows strong bands at 1780, 1690, 1515, 1495, 1292, 1240, 1205 and 977 cm⁻¹.

The NMR-spectrum (CD₃OD) shows peaks at δ = 1.45 (s), 1.48 (s), 1.53 (s), 1.60 (s), 4.47 (s), 4.57 (s), 4.65 (s), 5.17 (s), 5.40–5.80 (m), 5.95 (s), 6.90–7.80 (m) and 7.55 (s), TMS being used as internal reference.

EXAMPLE 3b

A. 6 β -(D- α -azido- α -phenylacetamido)-penicillanoyloxymethyl benzylpenicillinate

To a solution of chloromethyl benzylpenicillinate (2 g.) - prepared as described below — in dimethylformamide (30 ml.) is added potassium D- α -azidobenzylpenicillinate (2.1 g.).

After stirring overnight at room temperature the mixture is diluted with ethyl acetate (100 ml.) and extracted with water (2 $\times$ 25 ml.), 2% aqueous sodium bicarbonate (25 ml.) and water (2 $\times$ 25 ml.). The organic phase is dried and evaporated to dryness in vacuo to yield the desired compound as an amorphous powder.

The IR-spectrum (CHCl₃) shows strong bands at 2130, 1785, 1668, 1510, 1295 and 980 cm⁻¹.

The NMR-spectrum (CDCl₃) shows peaks at δ = 1.47 (s), 1.52 (s), 1.63 (s), 3.63 (s), 4.42 (s), 4.48 (s), 5.13 (s), 5.40–5.90 (m), 5.88 (s), 7.33 (s), and 7.43 (s). (TMS being used as internal standard).

Preparation of the starting material:

Chloromethyl benzylpenicillinate

To a suspension of triethylammonium benzylpenicillinate (44 g.) in dimethylformamide (400 ml.) is added chloroiodomethane (40 ml.).

After stirring overnight the mixture is diluted with ethyl acetate (1200 ml.) and extracted with water (2 $\times$ 400 ml.) 2% aqueous sodium bicarbonate (100 ml.) and finally water (2 $\times$ 200 ml.).

The organic phase is dried, filtered and the filtrate evaporated in vacuo to give chloromethyl benzylpenicillinate as a dark, viscous oil.

The crude material is purified by dry column chromatography on silica gel (cyclohexane : ethyl acetate 7:3) and the pure chloromethyl benzylpenicillinate thus obtained is crystallized from ether : petroleum ether to yield colourless crystals with m.p. 92°–93°C.. [α]_D²⁰ = +179.8° (c = 1, CHCl₃)

The IR-spectrum (KBr) shows strong bands at: 1785, 1770, 1655, 1547, 1303, 1139, 1118 and 712 cm⁻¹.

The NMR-spectrum (CDCl₃) shows signals at δ = 1.51 (s), 3.64 (s), 4.41 (s), 5.53 (d J = 5), 5.68 (dd, J = 5, J = 9), 5.69 (d, J = 6), 5.85 (d, J = 6), 6.2 (d, J = 8–9), and 7.35 (s) ppm. TMS is used as internal reference.

B. 6 β -(D- α -amino- α -phenylacetamido)-penicillanoyloxymethyl benzylpenicillinate, hydrochloride

This compound is obtained from 6 β -(D- α -azido- α -phenylacetamido)-penicillanoyloxymethyl benzylpenicillinate by catalytic reduction, performed as described in Example 1b B. The aqueous phase is separated and freeze-dried to afford the desired compound as a colourless amorphous powder.

The IR-spectrum (KBr) shows strong bands at 1775, 1685, 1510, 1498, 1295, 1245, 1195, 1170, 1140 and 980 cm⁻¹.

The NMR-spectrum (CD₃OD) shows peaks at δ = 1.43 (s), 1.47 (s), 1.48 (s), 1.62 (s), 3.62 (s), 4.44 (s), 4.50 (s), 5.17 (s), 5.40–5.80 (m), 5.92 (s), 7.32 (s) and 7.52 (s). (TMS being used as internal standard).

Analogously to the procedure described in Example 3b A the following compounds are prepared from potassium D- α -azidobenzylpenicillinate and the chloromethyl esters of 2,6-dimethoxyphenylpenicillin, 5-methyl-3-phenyl-4-isoxazolylpenicillin, 3-(o-chlorophenyl)-5-methyl-4-isoxazolylpenicillin, and 3-(2,6-dichlorophenyl)-5-methyl-4-isoxazolylpenicillin:

6 β -(D- α -azido- α -phenylacetamido)-penicillanoyloxymethyl 2,6-dimethoxyphenylpenicillinate

6 β -(D- α -azido- α -phenylacetamido)-penicillanoyloxymethyl 3-(o-chlorophenyl)-5-methyl-4-isoxazolylpenicillinate

6 β -(D- α -azido- α -phenylacetamido)-penicillanoyloxymethyl 3-(2,6-dichlorophenyl)-5-methyl-4-isoxazolylpenicillinate

These compounds are converted into the hydrochlorides of the corresponding amino-compounds by reduction of the azido groups as described in Example 1b B.

EXAMPLE 4 b

A. Bis(6 β -phenylacetamido-penicillanoyloxy)-methane

To a stirred suspension of potassium benzylpenicillinate (22.3 g.) in dimethylformamide (110 ml.) is added chloroiodomethane (5.3 g.). After stirring for 48 hours at room temperature the mixture is diluted with ethyl

acetate (330 ml.) and extracted with water (2 x 60 ml.), 2% aqueous sodium bicarbonate (60 ml.) and water (2 x 60 ml.).

The organic phase is dried and evaporated to dryness in vacuo to yield the desired compound as an amorphous powder.

The IR-spectrum (CHCl₃) shows strong bands at 1780, 1675, 1505, 1290, 1135 and 982 cm⁻¹.

The NMR-spectrum (CDCl₃) shows peaks at δ = 1.45 (s), 3.63 (s), 4.39 (s), 5.60-5.80 (m), 5.85 (ss), 6.20 (d) and 7.33 (s). (TMS being used as internal standard).

B. 6 β -amino-penicillanoyloxymethyl benzylpenicillinate

To a solution of PCl₅ (0.97 g.) in dry, alcohol-free CHCl₃ (25 ml.) is added quinoline (1.07 ml.) with stirring. The solution is cooled to -10° C. and bis-(6 β -phenylacetamido-penicillanoyloxy)-methane (1.36 g.) is added. After stirring for 15 minutes at -10° C. n-propyl alcohol (5.1 ml.) is added. The temperature is kept at -10° C. for a further 15 minutes. Then the mixture is poured into water (25 ml.) and petroleum ether (55 ml.) is added.

The aqueous phase is separated and the pH adjusted to 7.5 by addition of sodium bicarbonate. The aqueous phase is extracted with ether (25 ml.). The organic phase is separated, dried and evaporated to dryness in vacuo to yield a mixture of the desired compound and quinoline.

Extraction of the residue with petroleum ether (3 x 10 ml.) removes the quinoline and leaves the desired compound as an amorphous powder.

The NMR-spectrum (CDCl₃) shows peaks at δ = 1.45 (s), 1.50 (s), 1.63 (s), 2.25 (broad singlet), 3.63 (s), 4.42 (s), 4.58 (d), J = 4.5, 5.40-5.80 (m), 5.87 (s), and 7.33 (s). (TMS being used as internal standard).

C. 6 β -(D- α -azido- α -phenylacetamido)-penicillanoyloxymethyl benzylpenicillinate

A solution of 6 β -amino-penicillanoyloxymethyl benzylpenicillinate (2.81 g.) and triethylamine (0.73 ml.) in ethyl acetate (30 ml.) is cooled to +5° C.. During 15 minutes a solution of D- α -azidophenylacetyl chloride (1.01 g.) in ethyl acetate (10 ml.) is added with stirring. The mixture is stirred for a further 30 minutes at +5° C. and then at room temperature for 1 hour. The mixture is washed with water, 0.01 N hydrochloric acid, 2% aqueous sodium bicarbonate and finally water. The organic phase is dried and evaporated in vacuo to yield the desired compound as an amorphous powder, identical with the compound described in Example 30 A.

EXAMPLE 5b

A. Bis-(6 β -amino-penicillanoyloxy)-methane

To a solution of PCl₅ (1.28 g.) in dry, alcohol-free CHCl₃ (30 ml.) is added quinoline (1.46 ml.) with stirring. The solution is cooled to -10° C. and bis-(6 β -phenylacetamido-penicillanoyloxy)-methane (1.36 g.) is added. After stirring for 15 minutes at -10° C. n-propyl alcohol (6.6 ml.) is added. The temperature is kept at -10° C. for a further 15 minutes. Then the mixture is poured into water (50 ml.) and petroleum ether (110 ml.) is added.

The aqueous phase is separated and the pH adjusted to 7.5 by addition of sodium bicarbonate. The aqueous phase is then extracted with ethyl acetate (3 x 25 ml.).

The organic phases are collected, dried and evaporated to dryness in vacuo to yield a mixture of the desired compound and quinoline. Extraction of the residue with petroleum ether (3 x 15 ml.) removes the

quinoline and leaves the desired compound as an amorphous powder.

The NMR-spectrum (CDCl₃) shows peaks at δ = 1.53 (s), 1.65 (s), 1.90 (broad singlet), 4.43 (s), 4.60 (d), J = 4.5, 5.50 (d), J = 4.5 and 5.90 (s). (TMS being used as internal standard).

B. Bis-[6 β -(D- α -azido- α -phenylacetamido)-penicillanoyloxy]-methane

A solution of bis-(6 β -amino-penicillanoyloxy)-methane (1.15 g.) and triethylamine (0.73 ml.) in ethyl acetate (20 ml.) is cooled to +5° C.. During 15 minutes a solution of D- α -azidophenylacetyl chloride (1.01 g.) in ethyl acetate (10 ml.) is added with stirring. The mixture is stirred for a further 30 minutes at +5° C. and then at room temperature for 1 hour. The mixture is washed with water, 0.01 N hydrochloric acid, 2% aqueous sodium bicarbonate and water. The organic phase is dried and evaporated in vacuo to yield the desired compound as an amorphous powder, identical with the compound described in Example 1 A.

In the case where R₄ represents a hydrogen atom, the intermediates of formula VIII can be used directly in the next step, and if R₄ represents a protective group this is first removed, e.g. by hydrogenation or hydrolysis.

In a next step the compounds of formula VIII (R₄=H) are reacted with a reactive derivative of an amide or a thioamide of the general formula IX:

in which R₁ and R₂ have the meanings defined before, and R₅ stands for O or S to yield the compounds of formula I.

The starting materials of formula IX are known or can be prepared by methods known from generally used textbooks.

The amides of formula IX can be well-known methods be transferred into reactive derivatives such as acid amide halides, acid amide dialkyl sulphate complexes or acid amide acetals. The acid amide halides used are preferably the chlorides or bromides, and they can be prepared by treating the amides with halogenating agents. It is preferred to use halogenating agents which throughout the reaction form gaseous by-products, such as phosgene, oxalyl halides, or thionyl halides, but also others may be used. The reaction can be performed in inert, dry, organic solvents, e.g. ether or toluene, in which the amide halide in most cases will be insoluble and from which it can be isolated by filtration after the reaction is completed. The acid amide halides are hygroscopic and rather unstable and are therefrom preferably used in the next step without purification.

The acid amide dialkyl sulphate complexes can be prepared by treating the amides with dialkyl sulphate, preferably dimethyl sulphate, under well-known conditions. By treating the acid amide dialkyl sulphate complexes with sodium lower alcoholates, e.g. sodium methoxide, acid amide acetals of the general formula IXa:

in which R_1 and R_2 have the meanings defined above and R_6 is a lower alkyl group, are formed, which acetals may also be used in the next step.

When acid thioamides are used as starting materials a reactive derivative in form of an acid thioamide alkyl halide complex can be formed by treatment with alkyl halides, e.g. lower-alkyl iodide. This reaction is well known from the chemical literature.

The reaction conditions for the reaction between the amide derivative and the compound of formula VIII depend on the reaction components used in the process. When acid amide acetals are used in the reaction with the compounds of formula VIII, the reaction temperature depends on the reaction components. The reaction is performed in inert organic solvents, for instance ether.

When acid amide halides, dialkyl sulphate complexes, or thioamide alkyl halide complexes are used, the reaction is also performed in inert organic solvents, which are dry and free from traces of alcohols, preferably chloroform, in which the reaction components are soluble, but solvents in which the starting materials are insoluble, e.g. ether, may be used as well. The reaction is performed under cooling and in the presence of at least one equivalent of a tertiary amine, for example trimethylamine, triethylamine, N,N -diisopropylethylamine or N -methylmorpholine. In the case where one equivalent of the tert. amine is used, the reaction product will be obtained as a salt when an acid amide halide is used, and as the free esters of formula I when the dialkyl sulphate complexes and thioamide alkyl halide complexes are used.

The reaction time depends on the reactants, the temperature and the solvents used in the process.

In another embodiment of the method, a compound of the above formula VI is reacted with a compound of the above formula VII under the same conditions as described above for the reaction between the compounds of formula IV and formula VII to yield a compound of formula X:

in which R_1 , R_2 and R_4 have the above defined meanings. In the case when R_4 is different from hydrogen, this protecting group has to be split off whereafter the reaction product of formula X, ($R_4=H$), is acylated with a reactive derivative of an acid R_3-COOH in which R_3 is as above defined to yield the compounds of the invention. This acylation process is well-known from the preparation of other semi-synthetic penicillins.

The invention will be further described in the following Examples which are not to be construed as limiting the invention.

EXAMPLE 1

6-[(Hexahydro-1H-azepin-1-yl)-methyleneamino]-penicillanoyloxymethyl benzylpenicillinate

To a suspension of sodium 6-[(hexahydro-1H-azepin-1-yl)-methyleneamino]-penicillanate (3.5 g.) in dimethylformamide (50 ml.) was added chloromethyl benzylpenicillinate (3.8 g.). After stirring at room temperature for 65 hours, the mixture was diluted with ethyl acetate (200 ml.) and washed with water (3 $\times$ 25 ml.). The organic phase was extracted with dilute hydrochloric acid (pH = 2.5). The aqueous phase was separated and made alkaline by adding sodium bicarbonate. The oil which separated was taken up in ethyl acetate and the solution was dried and evaporated to dryness in vacuo to yield the desired compound as an amorphous powder. The NMR-spectrum ($CDCl_3$) showed peaks at $\delta = 1.47$ (s), 1.65 (s), 1.58 (m), 3.37 (m), 3.63 (s), 4.38 (s), 4.40 (s), 5.08 (dd), 5.4 – 5.8 (m), 5.87 (s), 6.20 (d), 7.32 (s) and 7.59 (d) ppm. TMS was used as internal reference. The IR-spectrum ($CHCl_3$) showed strong bands at 1773, 1673 and 1630 cm^{-1} .

The starting materials used in the above example are prepared in the following manner:

6-[(Hexahydro-1H-azepin-1-yl)-methyleneamino]-penicillanic acid dihydrate.

A. 1-Hexamethyleneiminecarboxaldehyde dimethyl acetal was prepared from the N-formylhexamethyleneimine-dimethyl sulfate complex by reaction with sodium methoxide according to the method of Bredereck et al. (Chem. Ber. 101, 41 (1968)). The boiling point was 83 – 84°C./12 mm Hg.

B. 6-[(Hexahydro-1H-azepin-1-yl)-methyleneamino]-penicillanic acid dihydrate.

A solution of the above mentioned acid amide acetal (4.1 g.) in dry ether (100 ml.) was slowly added to a solution of trimethylsilyl 6-aminopenicillanate (6.8 g.) in ether (500 ml.) at –30°C. with stirring. The temperature was raised to 0° within half an hour. Water (300 ml.) was added. The stirring was continued for ten minutes whereafter the aqueous phase was separated, extracted with ether and freeze-dried. The solid product was crystallized from methanol-acetone. It melted with decomposition from 135° to 142°C..

Sodium 6-[(hexahydro-1H-azepin-1-yl)-methyleneamino]-penicillanate.

To a solution of 6-[(hexahydro-1H-azepin-1-yl)-methyleneamino]-penicillanic acid dihydrate (13.3 g.) in dimethylformamide (120 ml.) was added sodium carbonate (3.7 g.). After stirring at room temperature for 10 minutes the desired compound crystallized. The crystals were filtered off and treated with abs. ethanol (110 ml.). Inorganic material was separated by filtration and ether (110 ml.) was added to the filtrate whereupon the desired sodium salt crystallized. The crystals were filtered off and used in the next step without further purification.

Chloromethyl benzylpenicillinate.

To a suspension of triethylammonium benzylpenicillinate (44 g) in dimethylformamide (400 ml) was added chloroiodomethane (40 ml).

After stirring overnight, the mixture was diluted with ethyl acetate (1,200 ml) and extracted with water (2 $\times$ 400 ml), 2% aqueous sodium bicarbonate (100 ml) and finally water (2 $\times$ 200 ml).

The organic phase was dried and evaporated in vacuo to yield chloromethyl benzylpenicillinate as a dark, viscous oil, which could be used in the next step without further purification.

A sample of the crude ester was purified by dry column chromatography on silica gel (Eluent: ethyl acetate).

25

ane-ethyl acetate 7:3) and the pure chloromethyl benzylpenicillinate thus obtained crystallized from ether: petroleum ether to yield colourless crystals with m.p. 92° – 93° C.

$[\alpha]_D^{20} = +179.8^\circ (c = 1, \text{CHCl}_3)$.

The IR-spectrum (KBr) showed strong bands at: 1785, 1770, 1655, 1547, 1303, 1139, 1118 and 712 cm^{-1} .

The NMR-spectrum (CDCl_3) showed signals at $\delta = 1.51 (s), 3.64 (s), 4.41 (s), 5.53 (d, $J=5$), 5.68 (dd, $J = 5, J = 9$), 5.69 (d, $J = 6$), 5.85 (d, $J = 6$), 6.2 (d, $J = 8-9$), and 7.35 (s) ppm. TMS was used as internal reference.$

EXAMPLE 2

6-[(Hexahydro-1H-azepin-1-yl)-methyleneamino]-penicillanoyloxymethyl benzylpenicillinate, hydrochloride.

A solution of 6-[(hexahydro-1H-azepin-1-yl)-methylene amino]-penicillanoyloxymethyl benzylpenicillinate in ethyl acetate was extracted with dilute hydrochloric acid ($\text{pH} = 2.5$). The aqueous phase was separated and freeze-dried to afford the desired compound as a colourless amorphous powder.

EXAMPLE 3

6-[(Hexahydro-1H-azepin-1-yl)-methyleneamino]-penicillanoyloxymethyl phenoxyethylpenicillinate.

This compound was obtained as described in Example 1 by using chloromethyl phenoxyethylpenicillinate instead of chloromethyl benzylpenicillinate.

The NMR-spectrum (CDCl_3) showed peaks at $\delta = 1.51 (s), 1.53 (s), 1.60 (s), 1.67 (s), 1.6 (m), 3.38 (m), 4.41 (s), 4.50 (s), 4.58 (s), 5.11 (dd), 5.3 – 5.8 (m), 5.90 (s), 6.8 – 7.6 (m) and 7.65 (d) ppm. TMS was used as internal reference.$

The IR-spectrum (CHCl_3) showed strong bands at 1768, 1685 and 1625 cm^{-1} .

Preparation of the starting material:

Chloromethyl phenoxyethylpenicillinate.

To a solution of phenoxyethylpenicillin (70 g) and triethylamine (29.4 ml) in dimethylformamide (250 ml) was added chloroiodomethane (80 ml), and the mixture was stirred for 3.5 hours at room temperature. Then the mixture was diluted with ethyl acetate (500 ml) and ether (500 ml), filtered, and the filtrate washed with water (3 $\times$ 250 ml), 0.5 M aqueous sodium bicarbonate (100 ml), and water (2 $\times$ 100 ml). The organic phase was dried and evaporated in vacuo to yield the crude ester as a brownish gum, which could be used for the next step without further purification.

EXAMPLE 4

6-[(Hexahydro-1H-azepin-1-yl)-methyleneamino]-penicillanoyloxymethyl phenoxyethylpenicillinate, hydrochloride.

A solution of 6-[(hexahydro-1H-azepin-1-yl)-methyleneamino]-penicillanoyloxymethyl phenoxyethylpenicillinate in ethyl acetate was extracted with dilute hydrochloric acid ($\text{pH} = 2.5$). The aqueous phase was freeze-dried to afford the desired compound as an amorphous powder.

EXAMPLE 5

Chloromethyl 6-[(hexahydro-1H-azepin-1-yl)-methyleneamino]-penicillanate.

To a suspension of sodium 6-[(hexahydro-1H-

26

azepin-1-yl)-methyleneamino]-penicillanate (0.5 g.) in dimethylformamide (5 ml) was added chloroiodomethane (1 ml). After stirring at room temperature for 3.5 hours the mixture was diluted with ethyl acetate (25 ml) and washed with water (3 $\times$ 5 ml).

The organic phase was extracted with dilute hydrochloric acid ($\text{pH} \sim 2.5$). The aqueous phase was separated and made alkaline by adding sodium bicarbonate. The oil which separated was taken up in ethyl acetate and the solution was dried and evaporated to dryness in vacuo to yield the desired compound as a yellow oil.

The NMR-spectrum (CDCl_3) showed peaks at $\delta = 1.55 (s), 1.68 (s), 1.62 (m), 3.45 (m), 4.42 (s), 5.20 (dd), 5.52 (d), 5.70 (d), 5.87 (d) and 7.66 (d) ppm$. TMS was used as internal reference.

EXAMPLE 6

6-[(Hexahydro-1H-azepin-1-yl)-methyleneamino]-penicillanoyloxymethyl benzylpenicillinate.

A solution of chloromethyl 6-[(hexahydro-1H-azepin-1-yl)-methyleneamino]-penicillanate (0.1 g) in dimethylformamide (2 ml) was stirred at room temperature with potassium benzylpenicillinate (0.1 g) for 65 hours. The mixture was diluted with ethyl acetate (8 ml) and washed with water (3 $\times$ 2 ml). The organic phase was dried and evaporated to dryness in vacuo to yield an amorphous powder. By thin layer chromatography on silica gel (Merck HF₂₅₄) in the following solvent systems the product had the following R_f -values:

I	n-butanol-acetic acid - water (4:1:1)	$R_f = 0.45$
II	n-butanol-acetic acid - water (4:1:5)(upper layer)	$R_f = 0.42$
III	n-butyl acetate-n-butanol-acetic acid-methanol-1/15M phosphate buffer solution ($\text{pH} = 5.8$)(80:15:40:5:24)	$R_f = 0.27$

These R_f -values were identical to those of an authentic sample.

EXAMPLE 7

A. 6-Amino-penicillanoyloxymethyl benzylpenicillinate.

To a suspension of potassium 6-amino-penicillanate (1.2 g) in dimethylformamide (20 ml) was added chloromethyl benzylpenicillinate (1.8 g). After stirring at room temperature for 48 hours the mixture was diluted with ethyl acetate (80 ml) and washed with water (3 $\times$ 10 ml). The organic phase was extracted with dilute hydrochloric acid ($\text{pH} = 2.5$). The aqueous phase was made alkaline by adding sodium bicarbonate. The oil which separated was taken up in ethyl acetate. The solution was dried and evaporated to dryness in vacuo to yield the desired compound as an amorphous powder.

The NMR-spectrum (CDCl_3) showed peaks at $\delta = 1.45 (s), 1.50 (s), 1.63 (s), 2.25 (bs), 3.63 (s), 4.42 (s), 4.58 (d), 5.4 – 5.8 (m), 5.87 (s) and 7.33 (s) ppm$. TMS was used as internal reference.

B. 6-[(Hexahydro-1H-azepin-1-yl)-methyleneamino]-penicillanoyloxymethyl benzylpenicillinate.

To N-formylhexamethyleneimine (1.3 g.) in dry ether (25 ml.) at 0°–5° was slowly added oxalyl chloride (0.85 ml.) in dry ether (5 ml.) with stirring. The mixture was stirred for 2 $\frac{1}{2}$ hours at 0°–5°. The amide chloride formed was filtered off and washed with dry ether. It was kept in an desiccator.

The crude amide chloride (180 mg) in dry chloroform (3 ml) was slowly added to a solution of 6-aminopenicillanoyloxymethyl benzylpenicillinate (560
